MEANS FOR DRAINING MOISTURE FROM
STEAM IN STEAM TURBINESHermannus van Tongeren, Heemstede,
NetherlandsApplication June 26, 1936, Serial No. 87,566
In the Netherlands July 2, 1935

3 Claims. (Cl. 253—76)

This invention relates to means for draining moisture from steam in steam turbines.

It is well known that in steam turbines, and especially in the low pressure stages thereof, part of the steam is condensed and that the water of condensation thus formed has a deteriorating action on the blades. The principal object of my invention is an improved construction whereby the water droplets, which are thrown by centrifugal force from the rotor or rotors, are collected—and thereafter discharged from the casing—in such a manner that they cannot possibly return into the blading.

With this object in view, I suggest to provide a circumferential groove in the inner wall of the casing, said groove being so disposed relative to the corresponding rotor that the droplets thrown radially outwards from the rotor can reach the body of water already present in the groove without contacting with any stationary part of the turbine. Since the body of water in the groove, owing to the impacts of the droplets thrown thereinto, has a circumferential speed not essentially smaller than that of the droplets, the latter will be caught thereby without considerable rebounding. It will easily be understood that such a gyrating mass of water surrounding the rotor is much better adapted to catch and hold the droplets than are stationary solid walls.

In order that my invention may be more fully understood by those skilled in the art, I shall now proceed to describe the same in further detail with reference to the annexed drawing, in which:

Fig. 1 is part of an axial section of an axial flow turbine,

Fig. 2 shows part of a cross-sectional view of said turbine, along the line II—II in Fig. 1,

Figs. 3, 4 and 5 illustrate parts of axial sections along the lines III—III, IV—IV and V—V, respectively, in Fig. 2,

Fig. 6 shows a modification as part of an axial section of another axial flow turbine,

Fig. 7 is part of a cross-sectional view of said turbine, along the line VII—VII in Fig. 6, and

Figs. 8, 9 and 10 are parts of axial sections along the lines VIII—VIII, IX—IX and X—X, respectively, in Fig. 7.

In Figs. 1—5, a rotary blade wheel is designated by 1, the turbine casing by 2. The numerals 3 and 4 indicate normally shaped fixed guide blade rims on either side of wheel 1. The butt strap or sealing ring 5 of the moving blades is provided, on the right hand side, i. e. on the outlet side, with a drip rim or edge 6, from which

the water droplets are radially thrown off. Surrounding said drip rim, the inner face of casing 2 has a circumferential collecting groove 7 machined therein. As shown, the depth of said groove is greatest in the radial plane passing through the drip rim, i. e. on the outlet side of the moving blades, and gradually decreases towards the radial plane passing through the inlet side of said blades. Through a small portion of the circumference, the sloping side wall of the groove 7 is recessed so as to form a sill 10 located at a somewhat smaller distance from the turbine axis than the bottom of the groove. Secured to said sill as by screws 8a is a nozzle 8 fitted at the inner end of a passage 9 provided in the wall of the casing 2 and serving to discharge water collecting in the groove.

When the turbine is in operation, the groove 7 will after a certain period of time be filled with a gyrating, annular body of water, the more or less cylindrical inner surface of which will be substantially flush with the sill 10. Any water flowing over said sill will be forced by its kinetic energy into the nozzle 8 and thus be discharged through the passage 9.

Figs. 3, 4 and 5 clearly show that any droplet thrown radially off the drip rim 6 will reach the level of the gyrating body of water in groove 7 and thus be caught and held by said water, without coming into contact with the radial right hand side wall of said groove or with any other stationary part of the casing.

It is not necessary to provide every rotor element traversed by more or less wet steam with a draining device as described. For instance, a group of rotor elements or blade wheels, only the last wheel on the outlet side of such group together with the part of the casing surrounding such wheel may be provided with a draining device.

Figs. 6—10 of the drawing illustrate another embodiment of my invention, wherein the butt strap 11 is provided with two drip rims 12 and 13 on the inlet and on the outlet side, respectively. Said drip rims are surrounded by water collecting grooves 14 and 15, respectively, machined in the turbine casing 2. Also in this case the depth of each groove is greatest in the radial plane of the corresponding drip rim. The grooves are separated from one another by an annular ridge 16, which through a small portion of its length is recessed to form a sill 17, to which the nozzle 8 of the discharge passage 9 is secured by screws 8a.

Secured to the inner face of the ridge 16 is a

flat ring 18, the side edges of which are suitably spaced from the opposite radial walls of the grooves 14 and 15, respectively, so that any droplets thrown from the drip rims 12, 13 can freely pass through the narrow slots thus formed without coming into contact with said walls.

5 The strap 18 acts as a shield or baffle having for its effect greatly to reduce the circumferential speed of the steam carried along by the butt strap 11. Owing thereto, the levels of the bodies of water in the grooves 14, 15 are not seriously disturbed by wave motion.

What I claim is:—

1. In a steam turbine, a casing, a rotor element provided with a radially directed drip rim, a circumferential water-collecting groove in the inner wall of the casing situated in radial alignment of said drip rim and with its bottom spaced from said rim and a water-discharging conduit 10 opening into said groove substantially level with said drip rim, the groove being so disposed and formed as to permit water droplets thrown by centrifugal force from said drip rim to collect in said groove thus providing an annular body of 15 water and to prevent said droplets from being thrown into direct contact with any stationary solid wall.

2. In a steam turbine, a casing, a rotor element provided with a radially directed drip rim, 20 a circumferential water-collecting groove in the inner wall of the casing situated in radial alignment of said drip rim and with its bottom spaced from said rim and a water-discharging conduit 25 opening into said groove substantially level with said drip rim, the groove being so disposed and formed as to permit water droplets thrown by centrifugal force from said drip rim to collect in said groove thus providing an annular body of water and to prevent said droplets from being thrown into direct contact with any stationary solid wall.

ment of said drip rim and with its bottom spaced from said rim and a water-discharging conduit opening into said groove substantially level with said drip rim, the groove being so disposed and formed as to permit water droplets thrown by 5 centrifugal force from said drip rim to collect in said groove thus providing an annular body of water and to prevent said droplets from being thrown into direct contact with any stationary solid wall, and an annular baffle secured to the 10 casing partly closing said groove leaving only a narrow circumferential slot in the radial plane of said drip rim.

3. In a steam turbine, a casing, a rotor element provided with a drip rim at its inlet and 15 outlet sides, a circumferential water-collecting groove in the inner wall of the casing opposite the inlet and outlet sides of said rotor element and in radial alignment with the respective drip rims, a circumferential ridge intermediate of said 20 grooves, a recess in said ridge forming a sill and a water-discharging conduit opening in said sill substantially level with the drip rims, the grooves being so disposed and formed as to permit water droplets thrown by centrifugal force from the 25 respective rims to collect in the respective grooves thus providing annular bodies of water in the bottoms of the grooves, said droplets not coming in direct contact with any stationary solid wall.
